UNITED STATES PATENT OFFICE.

EDWIN SPEIDEL, OF CRANSTON, RHODE ISLAND, ASSIGNOR TO STANDARD NECKCHAIN COMPANY, OF PROVIDENCE, RHODE ISLAND, A FIRM COMPRISING ALBERT SPEIDEL AND EDWIN SPEIDEL.

DESIGN FOR A LINK FOR NECK-CHAINS.

50,766.

Specification for Design.

Patented May 8, 1917.

Application filed February 17, 1917. Serial No. 149,364. Term of patent 7 years.

To all whom it may concern:

Be it known that I, EDWIN SPEIDEL, a subject of the Emperor of Germany, residing in the city of Cranston and county of Providence, State of Rhode Island, have invented a new, original, and ornamental Design for a Link for Neck-Chains, of which the following is a specification, reference being had to the accompanying drawing, forming part thereof.

Fig. 2— is a sectional edge view on line 2—2 of Fig. 1 and is on a larger scale than that shown in Fig. 1.

I claim:

The ornamental design for a link for neck chains, as shown.

EDWIN SPEIDEL.
